UNITED STATES PATENT OFFICE.

JOB E. HAMMOND, OF NEW BEDFORD, MASS., ASSIGNOR OF TWO-THIRDS HIS
RIGHT TO DAREUS P. GARDNER AND EBEN PIERCE, OF SAME PLACE.

IMPROVEMENT IN HINGED MASTS FOR VESSELS.

Specification forming part of Letters Patent No. **145,648**, dated December 16, 1873; application filed
December 4, 1873.

To all whom it may concern:

Be it known that I, JOB E. HAMMOND, of New Bedford, in the county of Bristol, in the State of Massachusetts, have invented certain Improvements in Boats, of which the following is a specification:

My invention relates to the hinging of the masts of boats above the deck. The object of my invention is ease in raising and lowering the masts of boats, either with the sails set or furled.

Figure 1 is a perspective view of my invention applied to the mast of a boat. Fig. 2 is an elevation with mast erect.

Fig. 1, A¹ is a boat; B', its mast; C¹, a hinge; D¹, fall; E¹, a tackle-block; f' f' f', chain-braces, which brace and secure the mast when raised.

Fig. 2, A², the boat; B, the mast; C², the hinge; D², the fall; E², the tackle-block.

The masts of boats being hinged nigh the

deck, as seen in Fig. 1, its operation may be noted. By pulling the fall with one hand, and raising the mast with the other hand, it will be seen that it will render the task of "stepping" the mast comparatively easy. When the mast is raised perpendicular, it is secured by the chain-braces. When it is desirable to lower the mast, the chain-brace is liberated and the fall slackened.

What I claim as my invention, and desire to secure by Letters Patent, is—

A boat's mast divided just above the deck into two parts, when arranged with hinged ferrules C¹ C², and pins and chain-braces f' f' f', all combined and operating substantially as and for the purpose set forth.

JOB E. HAMMOND.
